[57] CLAIM

The ornamental design for a floor-mounted display for displaying retail merchandise with top shelf, as shown and described.

DESCRIPTION

FIG. 1 is a top plan view of a floor-mounted display for displaying retail merchandise with top shelf with the top shelf removed showing my new design;

FIG. 2 is a front elevational view thereof;

FIG. 3 is a left side elevational view thereof;

FIG. 4 is a right side elevational view thereof;

FIG. 5 is a bottom plan view thereof;

FIG. 6 is a top plan view with the top shelf in place thereof;

FIG. 7 is a front elevational view of FIG. 6;

FIG. 8 is a perspective view of the display of FIG. 1; and,

FIG. 9 is a perspective view of the display of FIG. 6.

FIG. 4

FIG. 5

*FIG. 6FIG. 7*FIG. 8

FIG. 9
